H. H. MEYER

GRAIN SEPARATOR

Filed Oct. 23, 1922

INVENTOR.
HENRY H. MEYER.
BY HIS ATTORNEY.

BY HIS ATTORNEY
James F. Williamson

UNITED STATES PATENT OFFICE.

HENRY HERMAN MEYER, OF RED WING, MINNESOTA.

GRAIN SEPARATOR.

Application filed October 23, 1922. Serial No. 596,305.

To all whom it may concern:

Be it known that I, HENRY H. MEYER, a citizen of the United States, residing at Red Wing, in the county of Goodhue and State of Minnesota, have invented certain new and useful Improvements in Grain Separators; and I do hereby declare the following to be a full, clear, and exact description of the invention, such as will enable others skilled in the art to which it appertains to make and use the same.

This invention relates to a grain separator, and particularly to such a separator designed to clean grain and separate the same from other seeds, such as wild peas and similar seeds. It is desirable to quickly and efficiently separate the good grain from such foreign seeds both for the purpose of marketing and planting the grain.

It is an object of this invention, therefore, to provide a machine, by means of which a large quantity of grain can be quickly and efficiently separated or freed from such other seeds.

It is a further object of the invention to provide such a machine having an upwardly moving separating surface, which surface has a moving member adjacent its upper side operative to distribute the grain in a thin layer and to return the same to the apron so that the separation of the grain and seeds will be effected.

It is still another object of the invention to provide such a machine provided with a plurality of separating surfaces, which surfaces are preferably formed by a single endless apron.

It is more specifically an object of the invention to provide a machine having such an endless apron constituting two separating surfaces, together with means for varying the inclination of said surfaces and with means for collecting the seeds and grain.

These and other objects and advantages of the invention will be fully set forth in the following description made in connection with the accompanying drawings in which like reference characters refer to the same parts throughout the different views, and in which,

Fig. 1 is a view in side elevation of the machine;

Fig. 2 is a view in end elevation thereof, as seen from the right of Fig. 1;

Fig. 3 is a vertical section taken on the line 3—3 of Fig. 1, as indicated by the arrows;

Figs. 4 and 5 are enlarged views in end elevation showing an adjusting means of said machine;

Fig. 6 is a vertical section on an enlarged scale of a detail of the machine;

Fig. 7 is a plan view of such detail;

Fig. 8 is also a vertical section on an enlarged scale showing another detail of the machine; and

Fig. 9 is a vertical section on an enlarged scale showing a portion of the machine.

Referring to the drawings, the machine comprises a frame of general rectangular outline comprising spaced vertical members 1 at each end thereof which are connected by longitudinally inclined members 2. The main element of the device comprises an endless apron 3 which passes transversely over rollers extending longitudinally of said frame, a driving roller 4 extends between the end members 1 and is disposed at one upper corner of the frame and the apron also passes about a roller 5 at the side of the frame opposite the roller 4 and about rollers 6 and 7 disposed, respectively, above and below the roller 5 and at the opposite side of the frame therefrom. Another roller 8 is disposed outwardly of the roller 7 and slightly below the same. The apron 3 travels downwardly at one side of the frame from the roller 4, as indicated by the arrow in Fig. 3, thence under the roller 8 and over the roller 7, thence upwardly to the opposite side of the frame and around and over the roller 5, thence upwardly under and around the roller 6 and again to the roller 4. The roller 5 is journaled in vertically movable bearings 9 guided in slots 10 and the vertical members 1.

These bearings are adjustable by threaded bolts 11 extending through apertured brackets on the end members 1 and provided with adjusting wing nuts 12. The roller 7 also has its ends journaled in bearings 13 guided for movements in slots 14 in the end member 1 through which the ends of said roller pass and the bearings 13 are also provided with bolts 15 extending upwardly therefrom and

2
having their upper ends threaded. These bolts 15 pass through apertured brackets extending outwardly slightly from the tops of the members 1 and are, likewise, provided with adjusting wing nuts 16. By operation of the nuts 12 and 16, the rollers 5 and 7 can be vertically moved to vary the inclination of the flights of the apron 3. The apron 3 is supported beneath each of its transverse flights by floors or platforms 17 and 18. Said platforms are at one side secured to and held in position by a bracket 19 supported about the ends of roller 5 and the floor 17 is supported at its other sides by brackets 20 secured thereto and to the end members 1. The floor 18 is supported at its other lower side by brackets 21 secured thereto and supported about the ends of the roller 7.

A trough member 22 is secured to the outer side of the frame and extends longitudinally thereof adjacent the roller 5, which trough has its outer side extending some distance above the upper flight of the apron 3. The trough 23 extends across the frame adjacent the end of the upper flight of apron 3, which trough communicates with a lower trough 24 extending across the frame at the end of the lower flight of the apron 3, which trough is provided with an outlet spout at its lower end. The trough 22 also has an extension 25 extending downwardly across one end of the frame and a discharge spout 26 is disposed adjacent the lower end of the roller 8 and also over the extension 25 so as to discharge therein.

A two-compartment hopper 27 is disposed at the upper end of the frame 1 and provided with outlet spouts 28, one of which delivers adjacent the upper end of the upper end of the upper flight of apron 3 and the other of which delivers adjacent the upper end of the lower flight of said apron. A slide 29 having one end formed as an operating handle is adapted to control the flow of material from both compartments of the hopper 27. The roller 4 has a journal extending at one end of the frame to which is secured a pulley 30 adapted to be driven by a belt connected to any suitable source of power.

In operation, the uncleaned grain containing the wild peas, or other seeds, is placed in the hopper 27 and the pulley 30 is driven to drive roller 4 and traverse the apron 3. The slide 29 now being operated, the material passes down through the spouts 28 and is delivered adjacent the upper corner of each flight of the apron 3. Each of these flights forms a plane separating surface inclined both longitudinally and transversely and the material tends to move toward the lower corner thereof. Owing to the motion of the apron, the material is carried upwardly on each of said surfaces. The material on the upper surface will be carried under

roller 6 and in passing around the same will be formed into a comparatively thin layer. The material will pass over the top of this roller and again drop onto the upper surface of the apron. The wild peas being round, will acquire momentum as they drop onto the surface and will roll down over the apron and the material thereon into the trough 22. The wheat or other grain will not acquire such momentum and will merely drop back onto the surface of the apron adjacent the roller. Such wheat or other grain will pass several times about the roller 6 as it moves longitudinally of the apron and will eventually be discharged into the trough 23, the same having been freed from the wild peas or similar seeds. The material discharged onto the surface of the lower flight of the apron 3 will move in a manner similar to that just described. Such material will be carried upwardly and pass around the roller 5 from the upper side of which it will again drop on the separating surface. The wild peas and similar seeds will thus acquire momentum and will roll over the separating surface and the material thereon to the lower side of said surface. It will be noted that a trough is formed at the lower side of the apron by the roller 8 and the apron. The peas will roll into this trough and pass longitudinally thereof into the spout 26. The peas discharged into trough 22 will move downwardly thereon and pass into the extension 25. The spout 26 discharging into the extension 25 all of the peas and other seeds will be discharged at one point. The grain which gravitates down the lower separating surface will be discharged into the trough 24 into which the grain from the upper surface is also passed so that all of the clean grain will be discharged at one point. The rollers 5 and 6, therefore, act both as guide rollers for the apron 3 and also as separating devices for the seeds. The transverse inclination of the separating surface can be varied to suit various conditions and kinds of material by adjustment of the nuts 12 and 16.

The upper and lower runs or flights of the apron 3 thus each forms a separating surface and the machine thus comprises, in effect, two separators. The material does not pass from the upper flight or apron 3 to the lower, or vice versa, but each flight with its associated roller and drum forms a distinct separating structure. These structures are, however, both formed and operated by one apron so that they are thus structurally and operatively combined.

From the above description it is seen that applicant has provided a comparatively simple and efficient machine for separating grain from foreign seeds and substances. The machine, owing to its plurality of sepa-

rating surfaces, has a large capacity and the various parts are efficiently used. The machine requires very little power and has few parts which have any tendency to be come disarranged. The efficiency of the machine has been demonstrated in actual practice.

It will, of course, be understood that various changes may be made in the form, arrangement, details and proportions of the parts without departing from the scope of applicant's invention, which, generally stated, consists in the matter shown and described and set forth in the appended claims.

15. What is claimed is:

1. A grain separating machine having in combination, an apron having an upwardly moving surface adapted to carry grain and other seeds, a movable device at the upper 20 end of said apron disposed above the same and under which the grain and seeds are adapted to pass in a thin layer, said device being operative to return said material over the top thereof back onto said apron.

25. 2. The structure set forth in claim 1, said movable device being moved by said apron.

3. A machine for separating grain and impurities, having in combination, an apron arranged to form two upwardly moving surfaces 30 adapted to carry grain and other seeds, devices at the upper end of each surface disposed above the same and under which the grain and seeds are adapted to pass, said device being operative to return said material over the top thereof and back to said surfaces.

35. 4. The structure set forth in claim 3, and means for varying the inclination of said surfaces.

40. 5. The structure set forth in claim 3, said devices constituting rollers forming guiding means for said apron.

45. 6. The structure set forth in claim 3, and troughs adjacent the lower side of each of said surfaces and extending longitudinally thereof.

7. The structure set forth in claim 3, and troughs adjacent the lower ends of each of said surfaces.

50. 8. A machine for separating grain and wild peas or similar seeds having in combination, an endless apron, a driving roller for moving the same, guide rollers for said apron so disposed that the apron forms 55 superposed upwardly moving separating surfaces, each of said surfaces having one of said guide rollers thereabove adjacent its upper side under which the grain and seeds

are adapted to pass, said rollers being operative to return said material from their upper sides back to the said surfaces.

60. 9. A machine for separating grain and wild peas or similar seeds having in combination, an endless apron, a driving roller for moving the same, guide rollers for said apron so disposed that the apron forms superposed upwardly moving separating surfaces, and a guide roller disposed at the lower side of one of said surfaces and below the same to form a trough extending longitudinally of said apron.

65. 10. The structure set forth in claim 9, said driving roller being disposed above the upper end of said upper surface.

70. 11. A grain separating machine having in combination, an endless longitudinally inclined apron, a guide roller at one side thereof, spaced guide rollers at the other side thereof disposed, respectively, above and below said roller whereby said apron has superposed transversely and upwardly inclined separating surfaces, a guide roller outwardly of and below the lower of said spaced rollers and a driving roller disposed above the upper one of said spaced rollers, said first mentioned roller and the upper one of said spaced rollers permitting passage of material carried by said surfaces thereunder and being operative to return said material from their top portions back to said surfaces.

75. 12. The structure set forth in claim 11, and means for moving said first mentioned roller and the lower one of said spaced rollers vertically to vary the inclination of said surface.

80. 13. A machine adapted to separate grain and wild peas and other seeds having in combination, a longitudinally inclined frame, an endless apron having superposed flights forming surfaces movable upwardly transversely of said frame, guide rollers above said apron at the upper side of each of said flights, said rollers forming separating devices under which material on said surfaces passes, said devices being operable to return said material to said surfaces, a trough along the lower side of each of said flights, and a trough at the lower end of each of said flights.

85. 14. The structure set forth in claim 13, and a hopper at the upper end of said frame having discharge means delivering to the upper corner of each of said flights.

90. In testimony whereof I affix my signature. 115
HENRY HERMAN MEYER.
